UNITED STATES PATENT OFFICE.

EDWARD L. GAYLORD, OF BRIDGEPORT, CONNECTICUT.

MACHINE FOR CUTTING MOLDINGS.

SPECIFICATION forming part of Letters Patent No. 286,423, dated October 9, 1883.

Application filed July 5, 1883. (No model.)

To all whom it may concern:

Be it known that I, EDWARD L. GAYLORD, a citizen of the United States, residing at Bridgeport, in the county of Fairfield and State of Connecticut, have invented certain new and useful Improvements in Molding-Cutters; and I do hereby declare the following to be a full, clear, and exact description of the invention, such as will enable others skilled in the art to which it appertains to make and use the same.

My invention relates to certain novel and useful improvements in machines for cutting picture and other moldings, and has for its object to provide such a machine as shall be cheap of construction, positive in all its movements, and shall do the work quicker and in a better manner than has heretofore been done; and with these ends in view my invention consists in the details of construction and combination of elements, hereinafter fully and in detail explained, and then specifically designated by the claims.

In order that those skilled in the art to which my invention appertains may more fully understand its construction and operation, I will proceed to describe the same, referring by letters to the accompanying drawings, forming a part of this specification, in which—

Figure 1 is a side elevation of my improvement, showing the several parts in their operative position; Fig. 2, an enlarged front elevation of the upper portion of the same, the legs and foot-lever being broken away; Fig. 3, a plan view; Fig. 4, a detail sectional view, showing the connection between the shaft and the block; and Fig. 5, a detail plan view of the sliding plate.

Similar letters denote like parts in the several figures.

A are the legs, to which are bolted downwardly-projecting flanges B of bed-plate C. Just under the bed-plate and moving in suitable guideways is a sliding plate, D, the function of which will be hereinafter explained.

At the outer portion of this sliding plate is a lug, D', to which is pivotally attached the rod d, having a number of holes, d', at its upper end for adjustment, as will be presently explained.

To the forward corners of the sliding plate D are bolted standards E, which form vertical guideways, in which move the tongues f f' of the cutter-carrier F. This carrier is so constructed that its inner sides are inclined toward each other in rectangular planes, as seen at f², Fig. 3.

g are slots cut through the sides of the carrier F, through which pass bolts f⁴ into holes f³ of two cutting-knives, G, thereby securing said knives. The sides of the carrier to which the knives are secured being at right angles to each other, as hereinbefore set forth, the knives themselves are therefore in the same relation. The cutting-edges g' are diagonal or oblique, so that when they descend they will make a draw cut. Great power and certainty are insured by this arrangement of the knives, and the most delicate moldings are cut without splitting or marring in the least.

H is a rectangular recess in the sliding plate D, the upper edges, h, of which form cutting-edges, so that when the molding is placed on the sliding plate D, and the carrier caused to descend, the edges g' of the knives G will pass close to the said edges h, cutting the molding smoothly.

At the top of the carrier F is an upwardly-projecting lug, I, to which is pivoted the lever J. The rear end of this lever is supported by a pin, j', passing through rod d, and the forward end of said lever is supported by a pin, j'', passing through the rod K, the latter being pivoted by pin k passing through the actuating-lever L, which is secured to the shaft L'.

M are blocks bolted between the flanges M' to insure firmness. To the lower end of these blocks are secured inwardly-projecting lugs or pivots m, which fit into recesses in the shaft L'.

(See Fig. 4.) Cast with or secured to said shaft L' is a lever, N, projecting downwardly, and having an open head, N', through which passes a curved bar, O, having formed on its inner end a foot-piece, O'. This bar is adjusted in said head N' by means of set-screw n, to accommodate the height of any operator.

It will be readily seen that a greater stroke can be gotten from a treadle of this construction than from those now in use on machines of this character, which is of the greatest im-

portance where heavy work is to be done. I also add a weight, P, at the rear end of said bar O, to counterbalance the carrier F and keep it in an elevated position, as shown, and give momentum to the stroke, which does away with the use of springs, which latter occasion much loss of time and power.

At the rear corners of the sliding plate D are secured brackets d^2 , to which the rear ends 10 of springs Q are attached, their forward ends being secured at q to the frame. The tendency of these springs is to throw the sliding plate D forward. Also, near the rear edge of said plate is pivotally attached a connecting-rod, 15 R, (see Fig. 3,) the forward end of which is pivoted at r to the hand-lever S, which is pivoted to the bed-plate C by means of screw s. Also, at the point r is secured the dog T. This dog abuts against the ledge A', holding the 20 sliding plate D against the tension of the springs Q. The ledge A' is cast on the bed-plate, so as to extend upwardly therefrom, and forms a bearing against which the molding is pressed while being cut.

25 Bolted to the bed-plate C in any suitable manner are graduated rests U, on which long moldings are supported and measured. These rests are flush with the sliding plate, and the graduating-lines 1 2 3 4 5, &c., are oblique, as shown, in order to coincide with the oblique or diagonal cutting of the molding. For convenience, brackets W, one of which is shown 30 at Fig. 1, may be attached to the rear of the frame, to support work of any description.

35 The operation of my improvement is as follows: Having placed the molding to be cut on the sliding plate D, it is grasped tightly by the hand against the ledge A', when the treadle is operated by the foot, causing the carrier F, 40 with knives G, to descend below the edges h of the sliding plate. This will cut the molding nearly in two; but there will still remain a small part uncut, owing to the fact that the knives in their descent did not come close to

45 the ledge A', against which the back of the molding abuts. Now, it is obvious that this is an advantage, as the knives passing through the wood at first make a rough cut, which must be planed before a suitable finish is obtained.

50 Now, without removing the molding, the lever S is grasped and pulled forward, which will move the sliding plate D backward against the tension of the springs Q, and as the carrier F is secured in standards E, bolted to said 55 plate D, the angle f^2 of the knives will come in close proximity to the ledge A'. By causing the carrier and knives to descend again, the small portion of the molding that remained uncut will be cut, and at the same time a shaving will be taken off from the ends that were cut at the first descent of the knives, leaving the ends of the molding perfectly smooth without necessitating the use of a planer.

60 The advantage in the sliding of the plate D, and the carrying of the carrier and knives therewith, is that when there is a very heavy

molding to be cut it is operated on as follows: The dog T is turned back out of the way, as shown in dotted lines at Fig. 3, and by the action of the springs Q the sliding plate D will 70 be thrown forward. In this position the carrier F and knives G will be removed some distance from the ledge A'. The molding now being placed on the supports U and plate D, and the knives caused to descend, there will 75 be but a small portion cut from the molding. The knives being allowed to ascend and the lever S pulled partially forward, thereby moving the carrier and knives backward and nearer the ledge A', said knives are again caused 80 to descend, and will make a deeper cut, and so on the same operation continues until the molding has been entirely severed. By this means moldings of the largest size and of the hardest material may be readily cut. In 85 cutting moldings of unusual thickness, the normal position of the carrier and knives may be raised by simply withdrawing the pins j and j^2 , and raising the lever J, and then reinserting said pins in holes nearer the top of the 90 rods d K.

One of the most important advantages in my improvement is that the lever is stationary, and the molding therefore does not have to be moved at all, so that the latter can be 95 held firmly against the ledge, and the plate itself shifted without any necessity on the part of the operator for releasing his grasp on the molding, and also different cuts may be made as fast as the treadle can be worked; also, by 100 the swinging treadle I am enabled to get a greater vertical play of the knives with far greater power than in any machine of this class now in use; and by applying the power directly over the work, as clearly shown at 105 Fig. 1, the greatest possible force is communicated to the knives.

Having thus described my invention, what I claim as new, and desire to secure by Letters Patent, is—

110 1. In a machine for cutting moldings and the like, the vertically-reciprocating carrier having the cutting-knives secured thereto, in combination with the sliding plate actuated by springs, and means for operating said plate against the action of said springs, substantially as set forth.

115 2. In a machine for cutting moldings and the like, the sliding plate D, carrying the standards E, and vertically-reciprocating carrier F, with cutting-knives G secured thereto, in combination with the springs Q, and means for operating said plate against the action of the springs, and means for operating the carrier, substantially as set forth.

120 3. In a machine for cutting moldings and the like, the sliding plate D, actuated by springs Q, and having connecting-rod R pivoted thereto, in combination with the hand-lever S, pivoted to the bed-plate, dog T, and ledge A', projecting upward from the bed-plate, substantially as shown and described.

4. In a machine for cutting moldings and the like, the combination of the sliding plate D, actuated by springs Q and carrying standards E, rod d, lever J, attached to the carrier 5 F, knives G, rod K, actuating-lever L, and swinging treadle N O, carrying weight P; substantially as described.

In testimony whereof I affix my signature in presence of two witnesses.

EDWARD L. GAYLORD.
